APRON

Filed Dec. 17, 1925

Inventor:
Benjamin Berkowitz
By *J. S. Sonnenfeld*
Attorney.

UNITED STATES PATENT OFFICE.

BENJAMIN BERKOWITZ, OF PHILADELPHIA, PENNSYLVANIA.

APRON.

Application filed December 17, 1925. Serial No. 75,923.

To all whom it may concern:

Be it known that I, BENJAMIN BERKOWITZ, a citizen of the United States, residing at Philadelphia, in the county of Philadelphia and State of Pennsylvania, have invented certain Improvements in Aprons, of which the following is a specification.

My invention is designed to provide an apron having means for protecting the strings thereof from strains or detachment during laundering without detracting from the appearance of the apron when in use and the leading object of my invention is the avoidance of the formation of casings extending across the fronts of aprons, which form lumps or pads interfering with laundering or mangling and give a bulky and unsightly appearance, as well as necessitating use of an excessive amount of material.

In accordance with my improvements, tunnels are formed by hems or facings along the lateral or vertical edges of the apron with open mouths adjacent to the points of attachment of the strings. Such tunnels are preferably formed along the longitudinal edges of the apron bib and avoid the objections inherent in the provision of tunnels or casings extending transversely to the length of the apron and across the body of the wearer.

The characteristic features and advantages of my invention will more fully appear from the following description and the accompanying drawing in illustration of a preferred embodiment thereof.

In the drawings, Fig. 1 is a front view of an apron embodying my improvements, with one string partly housed in its tunnel; Fig. 2 is a rear view thereof, with both strings free; Fig. 3 is a view of an implement for inserting the strings in the tunnels; and Fig. 4 is a fragmentary sectional view through the tunnel at the left of Fig. 1.

As illustrated in the drawings, the apron comprises an integral skirt 1 and bib 2, the latter having tapering edges 3 converging toward the top to permit free movement of the arms of the wearer. Tunnels 4 are formed along the edges 3 preferably by hemming over such edges. The tunnels extend from near the neck band 1' to approximately the waist line of the apron, where strings 5 are attached adjacent to the open mouths 6 of the tunnels, the attached ends of the strings preferably being housed within the tunnels.

A flexible rod 7 has on the ends thereof open eyes 8 over which the strings may be looped and pushed into the respective tunnels as indicated in Fig. 1; the strings being left in the tunnels in lapped sections upon the withdrawal of the rod and during laundering.

As each string is separately housed there is no danger of entanglement with one another and no bulk impeding laundering or mangling is formed at any one place. When the aprons have been laundered the strings may be readily extracted from the tunnels by pulling thereon with the fingers and the tunnels do not in any way effect the utility or appearance of the apron when worn.

Having described my invention, I claim:

An apron comprising a skirt and a bib with upwardly converging edges, strings secured to said apron adjacent to the waist line thereof and tunnels along the converging edges of such bib and having open mouths adjacent to the point of attachment of the strings.

In testimony whereof I have hereunto set my name this 15 day of December, 1925.

BENJAMIN BERKOWITZ.
